CLAIM

The ornamental design for a greeting card, as shown and described.

DESCRIPTION

FIG. 1 is a top plan view of a greeting card showing my new design, the broken lines shown represent a conventional fold line;

FIG. 2 is an enlarged right side elevational view, the undisclosed left side being substantially the same;

FIG. 3 is a greatly enlarged bottom plan view, the undisclosed top being substantially the same; and

FIG. 4 is a front perspective view thereof, in a folded position, the undisclosed rear being flat and plain.
